SHOE STRETCHER

Grant A. Fissel, Hanover, Pa.

Application February 13, 1939, Serial No. 256,040

2 Claims. (Cl. 12—128.6)

This invention relates to shoe stretchers of the type having a pivotal toe piece mounted on one end of a threaded rod, a heel piece threadedly mounted on the rod, and an operating handle at 5 the end of the rod opposite to the toe piece.

An object of the invention is to provide an improved stretcher in which the toe piece is pivotally connected to the threaded rod in such a manner that the device can be fitted into shoes 10 of various shapes and sizes.

In the accompanying drawing:

Figure 1 is a plan of a shoe stretcher embodying the invention;

Fig. 2 is a vertical longitudinal section of the 15 toe and heel portion of the structure shown in Fig. 1;

Fig. 3 is a vertical transverse section taken on the line 3—3 of Fig. 2; and

Fig. 4 is an inverted plan of the toe piece.

The improved shoe stretcher comprises a toe 20 piece 11 which is formed to allow the member to be fitted or inserted into the toe portion of a shoe. Preferably the toe piece 11 is constructed of cast metal of suitable thickness having a depending side wall 12 of suitable form which is substantially U-shaped in plan, as shown in Fig. 4. The portion 12 of the toe piece is open at the rear end of the toe piece, as shown in Figs. 1 and 2, so as to provide free swinging 25 movement of the toe piece 11 with respect to a threaded rod 13 which is connected at its forward end to the toe piece in the manner to be herein-after fully described. As shown, the toe piece has an upper or main wall, designated by the 30 number 11 and the side wall 12.

Depending from the central portion of the toe piece 11 and confined by the side wall 12, as shown in Fig. 3, is a boss 14. The boss 14 is substantially cylindrical in form and extending 35 from said boss forwardly towards the front end of the toe piece 11, is a reinforcing rib 15 (see Fig. 4).

The boss 14 is formed with a cylindrical bore 40 45 16 lengthwise therein. This bore extends the entire length of the boss and its lower portion is threaded for the reception of a plug 17.

The portion of the boss 14 opposite to the side of the boss to which the rib 15 is connected, is formed with an elongated slot 18. As shown in Fig. 3 the slot 18 is also coextensive with the length of the boss.

The threaded rod 13, adjacent its front end, is formed with a reduced portion 19 of suitable 50 55 length. This portion of the rod is adapted to be

disposed in the slotted portion 18 of the boss 14, as shown in Fig. 2.

The extremity of the rod 13 beyond the reduced portion 19 thereof, is formed with a spherical head 20 which is adapted to fit loosely within the bore 16, as shown in Fig. 2.

The construction of the toe piece 11 and the manner of connecting the forward end of the rod 13 to the toe piece, is such that the toe piece is free to move in all directions with respect to the 10 rod. Due to the manner in which the rod is connected to the toe piece, said toe piece can be easily detached from the rod by unscrewing the plug 17, in order that another toe piece of a different size or shape can be mounted on the 15 rod when desired.

Mounted on the rod 13 in spaced relation to the toe piece 11, is a heel piece 21 consisting of a main body portion and two spaced apart upwardly lugs 22 and 23. The lugs 22 and 23 are 20 formed respectively with aligned threaded openings 24 and 25, as shown in Fig. 2, for the rod 13.

The rear end of the rod 13 is provided with a handle 26, by which the rod is adapted to be turned to vary the distance between the toe 25 piece and the heel piece in well known manner.

Having thus described my invention, what I claim is:

1. A shoe stretcher comprising a threaded rod having a spherical head at one end thereof, a toe piece having a boss depending therefrom, said boss having a longitudinal bore formed therein for the headed end of said rod and an elongated slot formed therein for the portion of said rod rearwardly of the head whereby the rod is free 30 to move lengthwise of said boss, and a threaded plug mounted in the lower end of said boss for retaining the headed end of the rod within the boss.

2. A shoe stretcher comprising a threaded rod 40 having a spherical head at one end thereof, a toe piece having a substantially U-shaped side wall depending therefrom, a boss depending from the central portion of the toe piece and having a longitudinal bore formed therein for the headed 45 end of said rod, said rod having a reduced shank portion adjacent the headed end thereof, said boss having an elongated slot formed therein for the reduced shank portion of said rod, whereby the rod is free to move lengthwise of said boss, 50 and a threaded plug mounted in the lower end of said boss for retaining the headed end of the rod within the boss.
